UNITED STATES PATENT OFFICE.

WILLIAM WHEELER, OF CONCORD, MASSACHUSETTS.

FOCUS-REGULATOR FOR ELECTRIC-ARC LAMPS.

SPECIFICATION forming part of Letters Patent No. 280,426, dated July 3, 1883.

Application filed March 29, 1881. (No model.)

To all whom it may concern:

Be it known that I, WILLIAM WHEELER, of Concord, in the county of Middlesex and State of Massachusetts, have invented certain new and useful Improvements in Focusing Lamps; and I do hereby declare the following to be a full and exact description of the invention, such as will enable others skilled in the art to which it pertains to make and use it, reference being had to the accompanying drawings, which form part of this specification.

My invention is especially designed to provide a new or improved method and apparatus for automatically adjusting and maintaining the arc of an electric lamp in a fixed position or in any desired focus, whatever be the rates or the ratio of the consumption of the two carbon pencils of said lamp or the variations thereof.

This invention is also adapted to the like adjustment of the flame of a candle, or of any source of artificial light subject to changes of position through the gradual consumption of the light-producing substance. It is especially adapted, however, for use in electric lamps, to which this specification, therefore, particularly refers. The necessity of maintaining the electric light in a fixed position is very evident when it is used in connection with reflectors, lenses, or other optical appliances. It is of material importance in lamps in which the carbons are held by friction rollers or carriers or other devices through which the current passes to said carbons, since by this means the resistance of the current is rendered constant in amount, being determined by the uniform length of the carbon between said carrier and the fixed arc. It is also desirable in common electric lamps which are provided with ground or opal glass globes for tempering the dispersion of the light to keep the arc as nearly as possible in the center of the globe.

Heretofore the maintenance of the electric arc in a fixed position has been attempted in various strictly mechanical devices, by which either the luminous effects are impaired or else the fixation of the arc is only approximately effected. Among the first of those appliances are those lamps in which one of the electrodes (usually the negative one) is so enlarged that its consumption becomes practically *nil*, such

enlargement causing a reduced light production, as well as obstructing its radiation, and those in which the electrodes are placed at an angle with each other, so that the arc is necessarily maintained at their common intersection—a position well known to result in a diminished lighting efficiency. Among the second class are the majority of the most successful lamps, in which the carbon electrodes of equal size are held in the same straight line (usually a vertical one) in carriers so connected and actuated that the amount of feed motion imparted to the negative carrier is absolutely fixed at some invariable fraction (usually one-half) of that of the positive carrier to compensate for the unequal consumption of the two carbons under the action of a current of constant direction. This position of the carbons is the one most favorable to the economical production of light; but the arbitrary method of adjustment is only rudely approximate, since it operates quite independently of the variable rates and ratios of the consumption of the two carbons, which range from less than two to one to more than five to one.

By my invention the adjustment and maintenance of the source of light in any desired position is effected by means of certain apparatus whereby the luminous property of the light itself is caused to govern the motions of the materials by means of which said light is produced. Any change of the directions in which light radiates from the source toward a certain fixed part of the apparatus, such as would be caused by the slightest movement of said source from its normal position, directly causes such a movement of the light-producing material as to restore the light to its prescribed position. Hence, since the least error in the position of the light is made the agent for its own correction, the desired result is secured automatically with invariable accuracy, and under any variations in the rate and ratio of consumption of the light-producing material.

Figures 1, 2, and 3 of the aforesaid drawings represent isometric projections; and Fig. 4, a side elevation of different modifications of this invention, to be fully explained hereinafter.

In Fig. 1, A denotes the arc in an electric

lamp, of which the parts essential to this description are shown.

B represents a prism or reflector fixed adjustably or otherwise in any convenient position, so as to intercept the beam of light radiating from said arc at about right angles with the line of the carbons, and to reflect said beam at a right angle, or thereabout, so that it falls normally in the open space between, and on the adjoining edges of a pair of selenium "cells," commonly so called, (represented at C C" and C' C'", respectively, and fully described hereinafter.) As shown in Fig. 1, each cell is double, consisting, practically, of two cells adjoining each other and separated by any non-conducting film. Each section consists of two wires or conductors separated by and embedded in a thin layer of selenium, suitably prepared so as to develop a state of allotropy, in which its electrical conductivity is most sensitively affected by light, and formed into "cells," so called, presenting a relatively large extent of light-absorbing surface. The said cells are designed to offer variable electrical resistances, depending (inversely) upon the amount and intensity of the light falling thereon, and to offer equal resistances under equal illumination; hence, for the purposes of this invention, they may be defined to be any cells or devices presenting variable electrical resistance under the effect of light and heat, or either of them. Said cells are excluded as far as possible from the action of any other light than that which comes from the arc A through the reflector B.

D represents a small electromotor actuated by a small amount of the electric current derived through a suitable shunt, or otherwise, from the main conductor E E', and passing through the motor-conductor F, the two branches thereof, the cells C and C', and the commutator plates or brushes I and I', in proportions and directions determined by the relative conductivity of said cells, and returning to said main conductor through the cells C' and C''' and the conductor F, subject to the relative conductivity of said cells. The said motor D is of a well-known form, consisting of a fixed U-shaped magnet, between the two opposite poles of which is mounted a revolving armature, around which passes an insulated coil of conducting-wire. The two opposite ends of said coil are jointed to suitable commutators attached to one end of said armature after the usual manner, and the coil thereby placed in an electric circuit by the contact of said commutators with the commutator-brushes I and I', through which connection is made with the conductors F and F'. The passage of an electric current through the said motor—that is to say, through said coil around the armature thereof—results in the revolution of said armature, caused, as is well known, by the alternate attraction and repulsion taking place between the sides of the armature, together with the coil thereon and the

poles of the magnet, the direction of such revolution depending upon the direction in which the exciting-current traverses said coil. The motor connects by suitable gearing with the friction rollers or carriers G and H, through the latter of which the main current is conducted to produce the arc. The magnet of the motor D is represented in the drawings as of soft iron, magnetized by the electric current passing through a coil of the main conductor E E' around said magnet. Any part of the main current through the arc, or any other current, may be used for either of the purposes specified above, and a permanent magnet may be substituted in the motor; or any other suitable motor operated by electricity may be substituted for that shown.

Inasmuch as my invention does not refer to the regulation of the distance between the carbons or to regulators specifically so called, but to the focusing or adjustment in position of that part of the lamp which controls the position of the light simply, hence the lower carbon is represented in the drawings as the one to be actuated by the said motor.

With this construction the operation of the combination shown in Fig. 1 may be thus described: The main circuit passes through the conductor E E', the carrier H, the carbon pencils, the arc A, &c. A certain amount of the said current, which may be any desired part, or the whole, if need be, is shunted and made to pass *via* the conductor F F'. Between F and F' two paths or circuits of equal but variable electrical resistances are interposed for the passage of said shunted current. Between these two circuits interposing variable electrical resistances the said current divides itself or is divided into two currents, each one of which passes through the motor D on a common conductor or coil, above described, but in opposite directions, and in proportions governed by the relative resistances presented by the double selenium cells C C" and C' C'''. So long as the arc A is in or nearly in its normal position the beam of light intercepted and reflected by the prism B falls equally upon said cells, which may be of greater or less distance apart, as desired. They are, then, equally illumined, and therefore interpose equal resistances to the two divisions of the shunted current; hence the same quantity and intensity of current passes through the motor D in each of two opposite directions, said currents therefore neutralizing each other, causing no action of the motor, and hence leaving the arc undisturbed. [It is to be understood that in this description such terms and forms of expression are employed as are admissible in the popular theory regarding electrical currents, and as do not impair the practical significance of this specification.] Now, by the gradual consumption of the lower carbon the arc descends, whereupon the reflected beam falls more upon the double cell C C" and less upon the cell C' C''', and the former becomes a bet-

ter and the latter a poorer conductor than before. Their relative conductivity is instantaneously and substantially changed, and hence the path of least resistance is taken by the 5 larger part of the shunted current. That path is then as follows: from the common conductor F, through the half-cell C, the commutator plate or brush I, the coil of the revolving armature of the motor D, the plate or brush 10 I', and the half-cell C' to the common conductor or F'. The motor D is thereby actuated and revolved in such direction that the lower carbon is moved and adjusted in such manner as to restore the arc to its normal position. If, from 15 any cause, the arc should tend to move upward, or in the opposite direction from that already described, the reflected beam would fall more upon the double cell C' C'' and less upon the cell C C', and the conditions of conductivity in the two motor-circuits would be the reverse of that described above. The path of least resistance, which would be taken by the major part of the shunted or motor current, would then be as follows: from the common conductor F, through the half-cell C', the commutator plate or brush I', the coil of the armature of the motor D, (in the opposite direction from that in the case first described,) 25 the plate or brush I, and the half-cell C'' to the common conductor F' again; whereby the rotation of the motor would be reversed and the arc brought to a focus again.

In practice the arc has a constant tendency to move in one direction, and that movement is counteracted by means of this invention; 35 not intermittently, as explained above for convenience, but uniformly, the adjustment of the parts being such that when the arc is in its normal position the reflected beam falls a little more fully upon the double cell C C'' than upon the cell C' C'', and to just such an extent that the consequent rotation of the motor will exactly suffice under a current of uniform intensity through the arc, to supply the 40 lower carbon pencil at the same rate that it is consumed in said arc.

It is desirable that when the arc is in its normal position the beam of light shall fall upon about half of each cell, since then any 45 changes in the position of said arc produces the double effect noted above—namely, of reducing the conductivity of one cell while it increases that of the other. If the beam only fills or falls on the space between the two cells, such change in the position of the arc affects 55 only the cell toward which the movement takes place, and then only in a less degree, since the outer margins of said beam are necessarily of less intensity than the inner part thereof; hence it is apparent that the two cells may be placed close together, if desired.

The combination described above can be simplified by omitting either the half-cells C and C' or the half-cells C'' C''' from the double 60 circuit, the conductors to be made continuous in place of said half-cells—that is to say, in-

stead of interposing a variable-resistance cell in each line on both sides of the electromotor it may be interposed on one side only—and for this either side may be taken, either before or 70 after the current passes through the motor. In such cases, however, it is advisable to substitute for the variable-resistance cells so omitted coils, cells, or other devices having each a fixed or constant electrical resistance equal to 75 that of the motor itself, or greater..

Fig. 2 represents a combination of two simple variable-resistance cells, C and C', with a novel form of motor, in which the armature is provided with two separate or distinct coils for 80 the conduction of the two opposing exciting-currents into which the motor-current is divided. J and J' represent the commutator plates or brushes, by means of which one of said coils is brought into the circuit in which 85 is the cell C; and K and K' represent the connections by which the other coil is placed in the same circuit with the other cell, C'. When the cell C is the one most illuminated by the reflected beam, it presents the least resistance, 90 and hence the greater part of the motor-current passes through that coil connecting with the brushes J and J'; and when the other cell is the one most influenced by said beam, the greater part of said motor-current passes 95 through the coil with which the brushes K and K' give connections. The said coils and connections are so arranged that the two currents of the same polarity pass around the armature in opposite directions; hence each one tends 100 to produce a revolution of the motor contrary in direction to that produced by the other, and, by means of suitable gearing, to so adjust and regulate the motion of the carbon connected therewith as to maintain the arc in 105 its proper and prescribed position, substantially as explained above.

L, L', and L'', Figs. 5, 6, and 7, represent transverse sections of the "Siemens armature," showing different methods of winding 110 them with two separate coils, so as to allow an equal efficiency to each coil. In the form shown at L the two coils cross each other diagonally at the ends of the armature. L' represents the two coils as wound on opposite 115 halves of the armature, while L'' shows greater mingling of the two coils. Other variations may be used without limit upon this and other forms of armatures and motors. I may also use two distinct armatures joined endwise or 120 longitudinally, and fixed upon a common axis of revolution—a device sufficiently evident to require no further illustration.

Fig. 3 represents another form or modification of my invention, in which the above-described prism or reflector is omitted, and a small opening through some intervening body—as a reflector or a card of metal or other suitable material—serves for the passage of the exciting beam of light, and for the fixed point 125 or pivot about or upon which said beam oscillates and turns as the arc rises and falls,

whereby said beam sends its rays directly upon one or both of the cells of variable resistance. A represents the electric arc in the focus of a parabolic reflector, A², through one side of which, in the horizontal plane of said focus, is formed an opening, which is provided or inclosed externally with a suitable case or box, M. The outer end or face of said case or box is made perpendicular to the said beam of light. The appearance of the said opening and case upon the inside of the reflector is shown for convenience in dotted lines upon the opposite side thereof at M'. The outer face of the case M is provided and fitted with a thin adjustable slide, N, in which is a small opening, through which the exciting or governing beam passes. Said perforated slide N is connected with the case M through or by means of the adjusting-screw O, by means of which said slide is moved up or down and the direction of the transmitted beam, together with its relation to the cells C and C', modified thereby. If desirable, the perforated slide N may be provided with a smaller adjustable slide, by which the aperture through the slide N may be diminished or enlarged, and the size of the transmitted beam varied in accordance with the size of the arc and the cells, the sensitiveness of the latter to the action of the light, &c.

It is also to be noticed that in the motor represented in Fig. 3, in combination with the single variable-resistance cells C and C', are two coils, x y, passing in opposite directions around the magnet itself, instead of around the armature, said coils being in the circuits of the two opposing currents regulated by said cells C and C'. Their united currents are then passed through the commutator plate or brush P and the single coil of the armature of the motor D, after a common fashion for motors, and rejoined with the main current through the plate P' and conductor F'. For the purpose of exciting the armature, the main current may be used, if for any reason—such as interposing a certain amount of resistance between the connections with the conductor F and F'—it should be desirable. When, now, the arc A begins to fall, the outer end of the exciting beam of light passing through M begins to rise, instantly rendering the cell C a better conductor and the cell C' a poorer one. The major portion of the current flowing through the conductor F will thereupon pass through the cell C and the magnet-coil y, nearer the front and right-hand side of the view, thereby causing the motor so to operate as to effect the required adjustment of the lower carbon, and hence of the arc A. If, however, the cell C' should become the better conductor by the upward movement of the said arc, the larger part of the current would pass through the said cell C' and the magnet-coil x, nearer the back and left-hand side of the view, thereby effecting the contrary adjustment or movement of the arc. In practice, the exciting beam of light, by automatic adjustment,

falls constantly upon the cell C more fully than on the cell C', to just the extent necessary to cause the carbon pencil or electrode to be moved toward the arc at the same rate that it is consumed therein, as previously explained. It will be seen, therefore, that the principal function of the secondary cell C' and its connecting-circuit is not to effect the downward or contrary movement of the adjustable carbon, but, primarily, to effect the counterpoise or neutrality of resistances, and of currents by which the carbon and the motor shall remain unmoved and fixed so long as the arc is in its proper position, and, secondarily, to more promptly effect the upward limit of the movement of the said carbon; also to increase the general sensitiveness of the apparatus, as previously described. It is evident, therefore, that the variable-resistance cells C can be substituted by a coil or cell of uniform resistance, said uniform resistance to be less than the maximum resistance of the remaining cell of variable resistance when the latter is the least exposed to the influence of the exciting beam of light, and to be greater than the minimum resistance of said cell of variable resistance when the latter is most exposed to the influence of the exciting beam of light. This invention therefore covers the use of such a cell of fixed resistance in substitution for one of the cells of variable resistance in any of the foregoing combinations.

Fig. 4 represents a side elevation of an electric or other lamp fitted with this invention, in which the prism B is mounted in the vertical column S or other support of said lamp—a form which may be used equally well with or without a reflector. The column S is hollow, and is provided with an opening for the admission of the exciting-beam at the same height as the lightsource. Within said column, fixed in the adjustable sliding carrier R, is the prism or reflector B, by means of which the exciting beam of light is thrown down upon and between the variable-resistance cells C and C', which, with the motor and other parts, are inclosed in a chamber beneath the light source, the lower part of the column S being enlarged toward the bottom, if required, to afford sufficient space for the necessary divergence and variation of said beam of light. The carrier R, holding the prism B, is adjustable by means of the thumb-screw T, connected therewith and with the top of the column or support S. The adjustment of the said carrier and prism may be better effected in certain cases by causing them to slide laterally in the line of the beam of light received by said prism in suitable ways formed in or upon said column S.

It is apparent that with any of the foregoing combinations, by inserting a candle or other light-producing device in the lower carrier or holder and providing only the motor-current described with the necessary circuit-connections, the apparatus described becomes a simple light-focusing device adapted for use with a light from any artificial source suscepti-

ble of such adjustment of position. Therefore I do not wish to confine myself to the use of an electric lamp as shown in the drawings; but any other lamp or artificial light source can 5 be used with equal results.

Having thus described my invention, what I claim as new, and desire to secure by Letters Patent, is—

1. In combination with devices for producing a beam of light or heat rays, two or more cells or devices, each of variable electrical resistance, depending upon the extent or nature of its exposure to the said rays, substantially as described, fixed in and constituting parts of 10 the parallel branches of a divided electrical circuit, substantially as set forth.

2. In combination with apparatus for producing a beam of light and heat, two cells or devices, substantially as described, interposing 15 in two parallel electrical circuits combined therewith variable ratios of their respective resistances under the variable influences of said beam, substantially as set forth.

3. In combination with a device for producing 20 a beam of light or heat, a cell or device of variable electrical resistance, depending upon its exposure to said beam, constituting a part of one branch of a divided electrical circuit, and a device of fixed electrical resistance 25 constituting a part of another branch of the same circuit, substantially as set forth.

4. In combination with means for producing 30 a beam of light or heat, two pairs of cells or devices, each pair of variable electrical resistance, according to its exposure to said beam, said pairs being so placed as to be oppositely affected by any operative change in their ex-

posure to said beam, and combined with each other in such manner that the first cell of each pair is directly connected with one pole of an 40 electric circuit, the second cell of each pair directly connected with the other pole of the circuit, each cell of each pair directly connected with both cells of the other pair, and the two cells of either pair joined with each 45 other through an electric motor operating in combination with said cells, all substantially as set forth.

5. In combination with means for producing and directing a beam of light or heat, the 50 cells or devices C C', having parallel circuit-connections through the motor D, substantially as set forth.

6. In combination with apparatus for producing a beam of light and heat, or either of 55 them, the case M, perforated slide N, and cells C C', all being substantially as set forth.

7. In an electric lamp, the combination of a reflector, A², having an opening, and case M, the perforated slide N, adjusting-screw O, cells 60 C C', electromotor D, and carbon-holders, substantially as set forth.

8. In an electric lamp, in combination with the column or support S, the prism B, cells C C', an adjusting-motor, substantially as set 65 forth.

9. In an electric lamp, in combination with the column S, the prism B, holder R, adjusting-screw T, and cells C C', substantially as set forth.
